METHOD AND MACHINE FOR PRODUCING
COILED WIRE BUNCHES

George L. Mason, Warehouse Point, Conn., assignor to Springfield Wire & Tinsel Co., West Springfield, Mass., a corporation of Massachusetts

Application March 10, 1934, Serial No. 714,899

13 Claims. (Cl. 140—71)

This invention relates to an improved method and machine for producing coiled wire bunches. It is especially adapted for coiling flat tinsel wire such as is commonly used in bunches for cleaning utensils. But the particular product of the machine may be any kind where coils of wire are wanted within the capacity of a machine operating on the same broad coiling principle as the present one.

10 The improved method consists in coiling one or more metallic wire strands, preferably flattened into helical form and then winding the coiled wire into skein form under a tension sufficient to keep the coils stretched out. As the skein is 15 formed the coils interlace, and when it is taken off the winding reel the coiled wire contracts so that the coils interlock and at the same time the skein as a whole contracts into the hand-size bunch which is desired for the final product.

20 The manner in which this is accomplished will appear from the description below.

The improved machine utilizes the well known principle that a wire under tension when pulled over the edge of a knife blade or a fairly sharp corner will be given a tendency to coil into coils and will do so when the tension is released. Machines operating on this principle have heretofore been known and used. My improved machine as compared to prior art machines has the advantage in the new and useful details of arrangement, construction, and mode of operation. These features will be apparent from a disclosure of the new machine in its preferred form and from the claims pointing out the improvements.

35 Referring to the drawings—

Fig. 1 is an end view of the left-hand half of the assembled machine; the other half would normally show at the right-hand side of line *a—a*, but is omitted because its parts are a mere 40 duplication of those shown;

Fig. 2 is a fragmentary top view of the machine of Fig. 1;

Fig. 3 is a fragmentary side view looking from the left of Fig. 1;

45 Fig. 4 is an enlargement of a small portion of Fig. 2;

Fig. 5 is a section on line 5—5 of Fig. 4;

Fig. 6 is a view looking from the left of Fig. 5;

50 Fig. 7 is an enlargement of a small portion of Fig. 2; and

Fig. 8 is an end view of the complete machine.

The machine shown is what may be termed a "gang" machine, in that exactly the same operations are carried on at a large number of 55 slightly separated places in the same frame. In

this respect it is like a spinning frame. A description of the general arrangement of the machine will first be given.

Referring to Fig. 8, there are two sides to the machine, each a substantial duplicate of the other. The details of these sides are best shown in Figs. 1 and 2 and will be later described. The general arrangement includes the drive shaft 1 for the left-hand side and the shaft 1' for the right-hand side, the latter being driven from the former. Shafts 1 and 1' are belt connected to shafts below (12 and 12' respectively), which in turn are belt connected to drive the series of wind-up reels conveniently located below the drive shafts, so that the speed of the wind-up 10 reels will have a fixed timed relation to the speed of the coiling mechanisms driven by shafts 1 and 1', as indicated. With this generally duplicated arrangement on each side of the machine, the specific arrangement of the detail series of 15 coiling mechanisms and their mode of operation will be best understood from the enlarged views 20 of Figs. 1 to 6.

The drive shaft 1 (Fig. 1) is driven by a pulley 2 on the far end of the shaft which is belted to a 25 motor. This drive shaft 1 has keyed thereon a plurality of rubber faced rolls 3 arranged in spaced relation from one end of the machine to the other, see Fig. 2. The right-hand side of the machine is just the same, only the parts there 30 are reversely arranged just as if the parts of Fig. 1 were turned around 180° and slightly spaced from the central plane *a—a* of the machine from the parts shown to form the other side of the 35 machine.

Each roll 3 is provided with a companion roll 4 that is also faced with rubber. The rubber faces of rolls 3 and 4 are of the same density. Each roll 4 is mounted independently in bearings at the forked ends of an arm 5. Each arm 5 is pivoted independently as at 6 to the frame. Its handle portion 7 extends outwardly at the side edge of the frame. A rod 8 on handle 7 extends upwardly through the frame and has an adjustable collar with a spring between it and the frame, to urge handle 7 upwardly and roll 4 into frictional driving contact with its companion roll 3. When handle 7 is pressed downwardly by the attendant, roll 4 is moved away from roll 3. Any one of the rolls 4 can be separated from its companion roll 3 by pressing down on its handle without disturbing the frictional engagement of any other pair of rolls.

A series of wind-up reels 11, made up with arms 9, are mounted in the frame below the rolls 3 and 11'

4. For each two sets of rolls 3 and 4, one wind-up reel 11 is provided. The number of wind-up reels in the whole machine is one-half the number of pairs of rolls 3 and 4. Each reel has a pulley 10 driven by a belt from shaft 12. The latter is driven by belt connection 13 from drive shaft 1.

A common curling rod in the form of a small round wire 14 is mounted horizontally at the top 10 of the machine, see Fig. 2. It extends from one end of the machine to the other and immediately above the pairs of rolls 3 and 4. It is supported in position from an upwardly extending bracket arm 15 at each end of the machine, by means of 15 a horizontal holder 16 bolted to these arms.

A longitudinal slot 17 (Fig. 5) divides the upper edge of the holder 16. The wire rod 14 rests on the bottom 18 of this slot 17, best shown in Figs. 5 and 6. Wire rod 14 is held in extended 20 position along the bottom 18 of the slot 17 and is clamped against each end of its holder 16 by a screw and washer, as shown at the bottom of Fig. 7.

Guide or cross slots 19 (see Fig. 6) are cut 25 across the upper edge of holder 16. There are three slots 19 provided immediately above each pair of rolls 3 and 4. Any one of these cross slots 19 may be used to guide material to the bite of the rolls below them. Cross slots 19 are much 30 deeper than the longitudinal slot 17, extending well below its bottom 18, as is clear from Fig. 6.

The curling rod 14 is supported in slot 17 throughout its length except where it bridges slots 19, forming at each of these slots a short 35 curling pin over which the wire to be curled is drawn.

A spool holder 20 (Figs. 1 and 2) is mounted 40 on the frame back of the series of rolls 3 and 4. A rigid spindle 21 is mounted on this holder and in position for its spool to unwind in line with each pair of rolls, one spool for each pair of rolls. The holder 20 and spindles 21 are set in inclined position. And a spool of wire 22 is placed on each spindle.

Each spool 22 has its bottom in flat frictional 45 contact with its holder 20, and the holder is faced with canvas strips for this contact. Rigid spindle 21 also has frictional contact with the interior surface of the spool hole. The weight of 50 the spool 22 against its stationary holder provides a drag on the spool's rotation whenever the wire is pulled off the spool.

Before starting the operation of the machine, supply spools 22 are placed on spindles 21, so as 55 to rest on spool holder 20. Each spool is filled with a supply of flat wire w. This wire is carried from the spool directly to and through a guide slot 19 (Fig. 5), bent over the curling pin formed by the portion of the wire 14, suspended across 60 that slot, and down to a pair of rolls 3 and 4. The spool, its set of guide slots 19, and its pair of rolls 3 and 4 are all in substantially the same vertical plane. Roll 4 is moved out of contact with roll 3 temporarily, by pressing down on 65 handle 7 to permit easy passing of the flat wire between the rolls. Two strands of flat wire are carried, one from each of two adjacent pairs of rolls 3 and 4, and tied on an arm 8 of a single wind-up reel 11 below the rolls, see Fig. 3. When 70 the flat wire from the desired number of spools is threaded to the machine in this manner, the power is turned on.

In operation the flat wire w is pulled upwardly 75 from its supply spool directly to the curling pin portion 14. It is pulled downwardly around the

curling pin, where it changes direction, and goes directly to the bite of and is fed between rolls 3 and 4. In this pulling of the wire by rolls 3 and 4 from the spool 22, a frictional drag against the rotation of the spool is set up at the spool 5 holder. This drag tensions the wire w between its supply on the spool and the bite of the rolls 3 and 4. The effect of this movement under tension and with a change of direction, over the curling pin, is to give the wire a tendency to curl 10 into coils. But the tension between the rolls 3 and 4 and the spool 22 is always sufficient to prevent any actual curling of the wire above rolls 3 and 4.

The reel 11 is rotated to take up the treated 15 wire and wind it into skein form or loops. The peripheral speed of the reel arms 9 is arranged to wind up the treated wire under tension, but this wind-up tension is not sufficient to prevent curling of the wire below rolls 3 and 4, as indicated in Figs. 1 and 3. It does curl into helical coils between the rolls and the reel. The wind-up tension is sufficient, however, to keep the helical coils stretched out. In this tensioned condition two strands of the coiled wire are wound 25 into adjacent loops until enough is wound to make up a single skein for a desired handful of coiled wire. The coils of each wire are opened up enough to overlap in adjacent loops so that they will interlock better when the winding tension is released. As will appear from Fig. 3, the arms 9 are located a substantial distance from the axis of the reel, so that when the reel is filled the thickness of material wound in skein form is relatively thin. This presents the advantage, 30 pointed out more in detail below, that there is not any great difference between the stretch given to the inner and outer turns. The skein will thus contract about equally throughout. Fig. 3 illustrates clearly the relative thinness to which 35 the body of the skein is wound, the distance between the outer surfaces of the arms 9 and the circumference of the circular head of the reel in the embodiment shown giving an approximate measure of the thickness of material built up 40 when the reel is filled.

When the reel 11 is thus filled, the machine attendant uses a pair of hand scissors to cut the wire below the rolls 3 and 4 and above the reel 50 11. He then grasps the skein that is tensioned on reel arms 9 and pulls it off the ends of the arms. The release of the tensioned skein results in its contraction. The skein pulls into a smaller compass or body than that in which it is wound. 55 This helps to mat the coils in the bunch, with these coils for the most part interlocked, due to the winding tension which held them slightly stretched for interlocking purposes. After removing one bunch of coils from a reel 11, the 60 attendant ties the loose ends of a pair of wires w extending from the two sets of rolls 3 and 4 to the empty reel of that set for the machine winding of another bunch.

It is not necessary to stop the machine to 65 empty the reels 11 by hand, or to replace an empty spool 22 with a full one, or to thread the flat wire w through the machine from spool to reel. But it is necessary for the attendant to watch for the time when each reel needs emptying. It does need emptying many times before 70 its supply spool is empty. And the attendant is depended upon to intermittently cut off by hand scissors, from the machine operation as the latter is carried on, the right amount for each of 75

the bunch units produced from any and every spool on the machine.

The coiling machine consists in a series of coiling and skein winding devices arranged on a common frame with a common driving mechanism. Each coiling and skein winding device is a duplicate of that shown in the drawings. In the machine that I have built for use there are fifty combined coiling and skein winding devices 10 (two coiling elements and one winding element in each device), all coordinated with a common drive and operated by common attendants. The machine as shown is planned to make up bunches of coiled wire for use as pads of abradant material in cleaning kitchen utensils and other scouring purposes.

The arrangement of the plurality of coiling and reeling mechanisms and accessory devices, all in the manner shown and described, enables one to 20 get a very large production from the one machine. With this machine a single attendant can service the large volume of production with great convenience. By putting a counter on shaft 1 the attendant can arrange the production so that 25 he can take off the bunches formed on the reels when they are of the right weight and without stopping the machine. If he starts at one end to do this work, starting a new bunch as he takes off the finished one, he will get the machine in 30 step with his take-off operations. As he takes a bunch off the reel he can hang it on the adjacent handle 7 and quickly service the machine from one end to the other. The whole operation is under his easy inspection at all times so 35 anything starts to go wrong he can quickly correct it. For example, he sees whether the wire is coiling properly as it travels from rolls 3 and 4 to the reel. If it is not, it may be due to lack of tension. He can put an annular weight on the 40 spool spindle to compensate for the loss of weight in the spool as it empties and correct the defect. If any wire breaks and whenever a bunch is cut off, it is exceedingly easy to thread the wire through the machine. All the attendant has to 45 do is press down on handle 7 and everything is open for the threading operation without the least danger to the operator.

One of the reasons that a wire coiling machine operating on the curling edge principle is liable 50 to turn out defective work is due to the wear of the wire against the stationary curling edge. This wearing away of the curling edge changes the character of the coils and ordinarily causes considerable expense in refinishing the edge. I 55 have made a special and improved curling edge arrangement. The single wire 14 is used as the curling edge for all the wire from the spools on one side of the machine. The wire from each spool may be applied for curling on any one of 60 the three portions of wire 14 that straddle the three slots 19 in front of each spool, see Figs. 5 and 6. When wire 14 is finally worn in all three portions so that it no longer gives good curling, the worn wire, which is inexpensive, can be 65 thrown away and a new one readily inserted in the holder 16. This construction with the easily renewable wire 14 as the curling edge saves a lot of expense.

The arrangement shown of curling the wire 70 under tension, partially releasing the tension to permit the coils to form and reeling up the wire into tensioned skeins, gives an advantage in production. For example, bunches of coiled wire are wanted in which the coils are effectively interlocked and matted together to retain the

bunched form. Where the mode of operation is as I have described it, with a properly fixed time relation between the driving means for the coiling mechanism and the driving means for the wind-up reels, the tension on the coils is only 5 partially released and the loops are wound with the coils opened up enough to overlap with adjacent coils. The bunch is formed in this way and then when the bunch is taken off the reel, the rest of the tension is released, whereupon the 10 coils all act under the tendency to come closer together or close up. This action has the effect of trapping overlapping coils in that position which gives an improved "mat" of tangled coils in the bunch. 15

It will be noted that by winding the tensioned curled strand into skein form and then permitting it to contract by its inherent elasticity into a hand-size bunch several advantages result as compared with winding the strand directly into a 20 form more nearly approximating the hand-size bunch which is desired as the final product. The bunch is more serviceable if it is compact and is held in this compact form by the inherent tension of the curled strand. At the same time it is 25 desirable to permit some stretching of the bunch to assist in cleaning it after use without causing any looseness in any part of the wound strand. If the required amount of curled strand were wound directly into the form of a hand-size 30 bunch there would be a very material difference between the radius and therefore the circumference of the inner and outer turns, and thus a large difference in the tensions imparted to these turns would result unless a complicated variable 35 speed drive were used. Any such large difference in tension would have undesirable effects. The inner turns being under a lesser tension than is desirable (unless the outer turns were stretched so much that their curls were largely straightened out), there would be a less firm interlocking of the curls and a tendency for these inner turns to become separated from the bunch during use. This would be particularly noticeable if the bunch were stretched out for cleaning. 40 There would also be a less firm interlocking of the outer strands on account of their being held stretched by the bunch and not being permitted to spring back into their natural condition with the curls closely spaced. 45

These difficulties are avoided, and an improved bunch obtained, by winding the bunch initially in skein form and then permitting it to contract into the desired size. The skein being of a relatively large diameter has a fewer number of 55 turns to accommodate the amount of material necessary to make the bunch, and there will be comparatively slight difference in radius and therefore in circumference between the inner and the outer turns. By the use of a very simple wind-up driven in timed relation to the delivery of the curled strand the strand can be tensioned substantially uniformly throughout its length and a substantially uniform spring-back allowed to all of the turns. Where the bunch is 60 wound initially in substantially its final size there will be a relatively small spring-back throughout its mass, but where it is wound initially in skein form the spring-back can be increased 65 while keeping a more uniform tension on the 70 curled strand throughout the bunch.

Having disclosed my improved machine in the form preferred for production purposes, I claim:

1. In a wire curling machine of the kind in which wire is drawn over a curling edge under 75

- 5 tension to give it a tendency to curl and then released to form coils, the combination of an aligned series of separate curling mechanisms, a common curling edge in the form of a small 10 wire over spaced portions of which the separate mechanisms draw wire to be treated under tension, a holder for supporting the curling edge wire in rigid position adjacent each of its spaced portions used for curling, and means to remove- 15 ably hold said wire in the holder.
- 10 2. The combination of claim 1 and said holder constructed with a longitudinal slot in which the curling edge wire is held on the bottom and transverse slots deeper than the longitudinal slot 15 arranged to suspend the curling edge wire at its spaced portions used for contact of the wire to be curled.
- 15 3. In a wiring curling machine of the kind described, a curling edge, drawing rolls to drag wire under tension over the curling edge, a wind-up reel and means to drive the drawing rolls and wind-up reel at such relative speed as to partially release the wire tension between the rolls and reel to form coils that still have tension 20 to keep them further apart than they otherwise would be and to wind the coiled wire in this condition.
- 20 4. In a wire curling machine of the kind described, a curling edge means, drawing rolls to drag a pair of wires under tension over said means, a single reel to receive the pair of wires and wind them up as a bunch of adjacent loops and means to drive the drawing rolls and reel at such relative speed as to partially release the 25 wire tension between the rolls and reel to form coils that still have tension to keep them further apart than they otherwise would be after the curling edge operation and to wind the pair of coiled wires in the same bunch under these conditions whereby when the bunch is taken from the reel they mat more firmly together.
- 25 5. In a wire curling machine, a frame having a drive shaft adjacent one top side, a series of rolls thereon, a second series of rolls spring 30 mounted to press into contact with the first series and form a series of pairs of drawing rolls along one top side of the machine, curling edge means located slightly above said series to serve said pairs of rolls, an inclined spool holder in back 35 of said rolls having an inclined spindle for each pair of rolls, the rolls, curling edge means and spool holder being arranged in triangular relation whereby wire may be fed for curling from spools on the holder over a sharp angle at the 40 curling edge and drawn by said rolls all in short easily reached paths at the top side of the machine.
- 40 6. In a wire coiling machine a frame, a pair of drawing rolls mounted at the top side edge, a driving shaft holding one roll parallel to said edge, a lever pivoted on the frame and having end bearings to hold the other roll, a spring 45 normally pressing the latter roll into contact with the drive roll and with the roll axes in substantially the same horizontal plane so the bight of the rolls is in substantially a vertical plane, said spring pressed roll being on the outer side and its lever forming a handle sticking out from the side of the machine to separate the rolls 50 when desired, a curling edge means mounted in substantially the same vertical plane as the bight of the rolls and slightly above the latter, a spool holder for a wire spool to feed directly to and over the curling edge to the bight of the rolls 55 making a sharp angle over said edge, said spool

holder being located on the frame a slight distance back of the drive roll, the rolls, curling edge and spool holder all located at the top side of the frame within reach of an attendant without change of position.

5

7. The combination of claim 6 and a wind-up reel driven in timed relation to the drive rolls, said reel being located slightly below the drive rolls and being also in reach of the attendant without changing his position for reaching the other elements of the combination.

8. The combination of claim 6 and a series of similarly mounted rolls spaced along the top edge of the frame, all having a common curling edge means and spool holder for spools to serve the rolls.

9. The combination in a wire coiling machine of the kind described, a rectangular table frame, sub-frames one overhanging each side edge of the main frame, each said sub-frame having 20 mounted on its top side at each of many slightly spaced stations a pair of wire drawing or tensioning rolls, one of which is readily moved out of contact with the other and forming their bight in a vertical plane, a common curling edge 25 means mounted in said vertical plane and extending transversely and slightly above the bight of all of said rolls on the sub-frame, a spool holder to serve for spools, one to feed each pair 30 of rolls, said holder being mounted slightly back of the sub-frame and on top of the table well below the curling edge means, all constructed and arranged for an attendant to reach all parts of the curling mechanism associated at a single 35 station without change of position.

35

10. The combination of claim 9 and a series of wind-up reels mounted just below each sub-frame and having a timed driving means with relation to the speed of the drawing rolls so that the wire being coiled will be wound up at less tension than that required to curl it by said curling means.

40

11. The combination in a wire coiling machine of an aligned series of wire coiling mechanisms for coiling a series of separate strands, a common driving means for said mechanisms, a series of wind-up reels arranged to form separate bunches of coiled wire as delivered from the coiling mechanisms, a common drive means for the wind-up reels, means to maintain a fixed timed 45 relation between the speeds of said two common driving means whereby the reels will hold the coils of the strands under tension and spaced far enough apart in the wind-up operations to help interlock the coils in the bunches when the latter are taken off the reels and their wind-up tension is released in such bunches.

45

12. The method of forming a flexible and resilient hand-sized bunch from a coreless helically curled metallic strand, which comprises supplying the curled strand at a substantially steady rate, winding the curled strand at a substantially constant rotative speed into the form of a skein of sufficient diameter to contain the material for a hand-sized bunch without substantial difference in tension between the inside and outside turns, maintaining the curled strand during winding under a tension sufficient to hold its curls opened out so that the curls in adjacent layers and turns will interengage when wound and when the skein is released will interlock to unite the skein into an integrated whole, the tension with which the skein is wound being sufficient to cause the skein as a whole when released to contract into a hand-sized bunch 70

60

65

70

75

75

with the central opening of the skein substantially closed, and releasing the skein from tension to permit the formation of a hand-sized bunch by contraction of the skein as a whole.

5 13. A machine for forming a flexible and resilient hand-sized bunch from a coreless helically curled metallic strand, which comprises a wire curling device supplying curled wire at a substantially steady rate, a reel with one end free for removal of a skein therefrom and of sufficient diameter to contain the material for a hand-sized bunch without substantial difference in circumference between the inside and outside turns, means for rotating the reel at a

10 15 substantially constant rotative speed so related

to the speed with which the strand is supplied as to impart to the curled strand a substantially constant tension sufficient to hold its curls opened out so that the curls in adjacent layers and turns will interengage when wound and when the skein is released will interlock to unite the skein into an integrated whole, the tension so imparted to the curled stand by the relative speeds of the curling device and the reel being sufficient to cause the skein as a whole when released by removing it over the free end of the reel to contract into a hand-sized bunch with the central opening of the skein substantially closed.
